UNITED STATES PATENT OFFICE

149,482

DESIGN FOR AN ORNAMENTAL LINK

John L. Garvin, New York, N. Y.

Application April 19, 1946, Serial No. 128,782

Term of patent 3½ years

(Cl. D45—4)

To all whom it may concern:

Be it known that I, John L. Garvin, a citizen of the United States, residing at New York, in the county of New York and State of New York, have invented a new, original, and ornamental Design for an Ornamental Link, of which the following is a specification, reference being had to the accompanying drawing, constituting a part thereof.

Fig. 1 is a front elevational view of an ornamental link, showing my new design; and

Fig. 2 is a side view thereof.

I claim:

The ornamental design for an ornamental link, substantially as shown.

JOHN L. GARVIN.
